US00D847203S

(12) **United States Design Patent** (10) Patent No.: **US D847,203 S**
(45) Date of Patent: **** Apr. 30, 2019**

(54) **DISPLAY SCREEN OR PORTION THEREOF WITH AN ICON**

(71) Applicant: **Siemens Healthcare GmbH**, Erlangen (DE)

(72) Inventor: **Roger Scrooby**, Nuremberg (DE)

(73) Assignee: **Siemens Healthcare GmbH**, Erlangen (DE)

(**) Term: **15 Years**

(21) Appl. No.: **29/633,229**

(22) Filed: **Jan. 12, 2018**

(30) **Foreign Application Priority Data**

Jul. 28, 2017 (EM) 004123842

(51) **LOC (11) Cl.** **14-04**

(52) **U.S. Cl.**

USPC **D14/490**; D14/489

(58) **Field of Classification Search**

USPC D14/485-495; D18/27, 33; D20/26, 34; D21/351

CPC ... B60K 37/00; G06F 3/0481; G06F 3/04845; G06F 3/04817; G06F 17/212; G06F 19/3406; G06T 13/80; G06T 15/02

See application file for complete search history.

(57) **CLAIM**

The ornamental design for a display screen or portion thereof with an icon, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen or portion thereof with an icon showing our new design.

The broken lines in the FIGURE are for the purpose of illustrating a display screen or a portion thereof and form no part of the claimed design.

1 Claim, 1 Drawing Sheet
(1 of 1 Drawing Sheet(s) Filed in Color)
